UNITED STATES PATENT OFFICE.

FRANK HESS, OF DAVENPORT, IOWA, ASSIGNOR TO DAVENPORT ICE CHIPPING MACHINE COMPANY, OF DAVENPORT, IOWA, A CORPORATION OF IOWA.

GEARING.

1,004,649.

Specification of Letters Patent.

Patented Oct. 3, 1911.

Application filed January 2, 1909. Serial No. 470,364.

To all whom it may concern:

Be it known that I, FRANK HESS, a citizen of the United States, and a resident of Davenport, in the county of Scott, in the State 5 of Iowa, have invented certain new and useful Improvements in Gearing for Operating Ice-Chipping Machines, of which the following is a full, clear, and exact description.

My invention relates to ice chipping machines, and particularly to that class of machines designed to chip or shave the ice into a finely divided state. The disintegration of ice in this manner has been done before, but the difficulties that have been experienced 15 arose from the irregularity of the pieces of ice and the trouble in handling the same; from the inability of the operator to shave pieces of ice when the same had been reduced to a very small size, and also from the 20 presence of water due to the melting of the ice shavings, before the latter had been deposited in a suitable receptacle.

The object of my invention is to overcome these difficulties, and in addition, to prevent 25 injury to the machine, through carelessness or otherwise, by automatically releasing the carrier employed to move the feeding device to the shaving-disk, from the actuating mechanism, when said feeding-device has 30 reached the limit of its advance movement, and also to enable the work of shaving ice to be done quickly and economically. This I accomplish by the means hereinafter fully described, and as particularly pointed out 35 in the claims.

In the drawings:—Figure 1 is a side elevation of my invention. Fig. 2 is a plan view thereof. Fig. 3 is a rear end elevation. Fig. 4 is a plan view of the carrier 40 for utilizing the motive power of the machine during the advance movement of the feeding device, broken away from the rest of the machine and drawn to a slightly larger scale. Fig. 5 is a vertical transverse section taken on dotted line 9—9 of Fig. 4 looking in the direction indicated by the arrows. Fig. 6 is a side view of the same looking at it from the rear of the machine and showing the clamping members of the carrier 45 closed and engaging the threaded drive-shaft. Fig. 7 is a similar view of said clamp-

ing members separated and disengaged from said threaded drive-shaft.

In the drawings A represents suitable standard, which is provided at a suitable point above its base with an arm A', the end of which has a vertical apertured boss in which the vertical post B' of a tray B, can be vertically adjusted by means of a set screw b. A short distance above the tray B, 55 standard A is provided with a forwardly projecting lug a, to which a drip-pail C is secured, preferably, by means of a lip a'. Detailed description of the attaching device of said pail is unnecessary, as any means 60 may be employed for this purpose.

The upper end of standard A terminates in a suitable supporting-frame K, that has an arm c projecting to one side, whose extremity is upturned and provided with bearings m, for a drive-shaft D, whose adjacent end extends through said bearings and is provided with a suitable crank D' with which to turn it. The opposite end of drive-shaft D extends concentrically through plate 70 d, that is preferably cast in one piece with the end of the post of the supporting-frame opposite arm c, transverse to the axis of the drive-shaft, and said opposite end is journaled in suitable bearings in the central boss 75 e of a circular case E, whose marginal edges are flanged circumferentially and secured by means of screws or otherwise to plate d. This case E is slightly pan-shaped, but quite shallow, and provides a chamber within 80 85 which the cutting-disk F revolves. A drain-pipe f leads from a suitable opening in its lowermost segment, and conveys the drippings from the chamber of the cutting disk into the drip-pail C, substantially as shown 90

In order to permit the ice to be fed to the cutting-disk, plate d is provided with a suitable opening j which is located at the rear of the drive-shaft and extends in a vertical direction, preferably, an equal distance both 95 above and below the horizontal plane of the same. The edge of this opening nearest drive-shaft D is vertical, and the edge farthest from said drive shaft is concentric therewith. A trough H, which is preferably cast in one piece with plate d and with the upper edge of the supporting-frame, ex- 100

tends from opening *j* toward the crank end of drive-shaft *D*. The longitudinal wall of this trough nearest the drive-shaft terminates, preferably, in a plane slightly below the axis of the drive-shaft, but the opposite wall thereof arises to very near the upper end of opening *j* and has lugs projecting rearwardly therefrom to which the knuckles of a hinged lid *J*, covering over the top of the trough, are pivotally connected. This lid *J* corresponds in transverse section to the upper portion of said opening *j*, and when it closes down upon the trough, forms four sides of the receptacle, in which the pieces of ice are deposited that are fed to the cutting-disk. Said lid is provided with a finger-grasp *i*, with which to raise or lower it, and with a spring snap *k* consisting of a flat piece of metal, the lower horizontal end of which is secured to the lid, and the upright portion of which has an opening therein which snaps over a suitable protuberance projecting rearwardly from plate *d*, when said lid is closed. By pulling back on the upper end of snap *k*, it can be disengaged from this protuberance, and said lid easily raised.

The end of the trough opposite plate *d* is open, and is, at the commencement of the operation of the machine, closed by a transverse feed-plate *I*, which is of such dimensions and contours that it fits within the closed trough. The feed-plate *I* is suitably secured to or cast in one piece with the rear end of a bracket *2*, which latter projects horizontally to the rear from a boss *3*, the bore of which is of such diameter that the drive-shaft can freely pass therethrough. This boss is connected with a longitudinally disposed sleeve *4* by means of a web *5*, and said sleeve is mounted on a smooth longitudinal and stationary shaft *6*. This shaft *6* is in the same horizontal plane as and is parallel with the drive-shaft, and has one end secured in a lug *7* projecting forward from the bearings *m* on the upper end of arm *c* of the supporting-frame, and has its opposite end secured in plate *d*. The end of boss *3* adjacent to said last mentioned bearings is provided with a vertical plate, which extends an equal distance both above and below the drive-shaft, the vertical surface of this plate, facing bearings *m*, is provided both above and below the drive-shaft, with headed studs *8*; *8*, and the barrel of these studs extend through vertical slots *9*, *9*, in the vertical flange *10*, of each of the semi-circular clamping-jaws *12*, *12*. The clamping jaws, when brought together, form a hollow cylinder, and their concave surfaces form a bore that corresponds in diameter to the drive-shaft *D*, and is provided with screw-threads that engage the screw-threads of said drive-shaft, extending from its

bearing in arm *c* of the supporting-frame, 65 to a point near plate *d*.

The upper edge *13* of flange *10* of the upper clamp *12*, and the lower edge *13* of the flange *10* of the lower clamp are, preferably, curved to conform to a circle struck 70 from the center of shaft *D* when said clamps are engaged by the same. These edges are beveled in a direction away from bearings *m*, and are simultaneously engaged by an upper and a lower cam, *14* and *15*. The 75 former, *14*, is secured to the upper end of a vertical spindle *16*, and the latter *15* to the lower end thereof, and this spindle is journaled in a vertically disposed bearing in the web 5 connecting boss *3* and sleeve *4*. The 80 under surface of the peripheral edge of the upper cam *14* is beveled, and the upper surface of the corresponding edge of the lower cam is likewise beveled, and when these cams are rotated in the proper direction, they engage the beveled edges *13* of the flanges of the clamps, and simultaneously move said clamps toward each other and into engagement with the threaded drive-shaft, and when said cams are rotated in the opposite 85 direction said clamps are automatically spread apart, out of engagement with shaft *B*, by virtue of the expansion of the coiled-springs *26*, interposed between the butt ends 90 of said clamps on each side of the drive-shaft, substantially as shown. The vertical movement of these clamps *12*, *12*, is guided, as they approach and recede from each other, by the guide-pins *17*, *17*, one end of each of which is permanently secured in one 95 of said clamps and the other end portion of each of which is made to reciprocate longitudinally in alining openings in the other clamp.

The lower portion of the boss of the upper cam *14* is provided with an arm *18* that projects toward the front of the machine, and this arm is provided with a handle on its end, and is held in said forwardly projecting position (against the tendency of the same to move into the position shown in dotted lines in Fig. 8, by reason of the expansive properties of springs *26*) by an overhanging finger *19* that drops down over the arm *18*, substantially as shown in Figs. 105 2, 3, and 4. This finger is secured to the outer end of a suitably curved arm *20* projecting from a boss *21*, journaled on a stud *22*, that projects forward from the side of sleeve *4*, and this boss has a downwardly 110 projecting arm *23*, whose lower end is curved toward plate *d*, which latter, at a point in longitudinal alinement with the end of said arm *23*, has a gage-screw *24*, tapped into it and locked in any position desired 115 within the limits of its adjustability by a locknut *25*.

The operation of my machine is as fol-

lows:—After said plate I is moved to the limit of its movement away from plate d, the lid of the trough is opened and ice placed in the trough and the lid closed again. Handle 18 is then pushed toward plate d as far as it will go, and the cams 14 and 15 made to engage the beveled edges of the flanges of the clamps, and cause the latter to simultaneously move toward 10 and engage the threaded drive-shaft D. When said handle has been moved as far as it can go, the finger 19 drops down over the arm of the same, and retains it in its forwardly projecting position, and thereby 15 keeps the clamps in engagement with the drive-shaft. Handle D' is then grasped and the drive-shaft turned in the proper direction, whereupon the boss of the carrier mechanism moves forward toward plate d 20 and carries the feed-plate with it. The small space intervening between the overhanging edge of the lid J and the vertical wall of the trough permitting bracket 2 to move forward with the said boss 3. When 25 the said plate has moved toward the cutting-disk as far as it is considered advisable for it to go, the end of the arm 23 will engage the head of the gage-bolt 24, and the continued revolution of the drive-shaft will 30 cause said arm 23 to move on its pivot and lift finger 19 from in front of the arm of the handle 8, and thereby permit the expansive power of springs 26, 26, to assert itself and force the clamps 12, 12, apart, out 35 of engagement with the threaded drive-shaft. When this is done the operator grasps the carrying mechanism with his hand, and draws it back as far as it will move on the drive-shaft and stationary 40 shaft 6, and then makes the clamps engage the threaded drive-shaft again and repeats the operation *ad libitum*.

What I claim as new is:—

1. In a machine of the kind specified, a 45 screw-threaded drive-shaft, a sleeve reciprocally mounted thereon, oppositely movable clamps carried by said sleeve having screw-threaded inner faces that engage said shaft when in operation and provided with wedge-blocks on their outer faces, a rock-spindle, cams mounted on the opposite ends of said spindle that engage said wedge-blocks and move the clamps toward each other, and devices that are adapted to lock said clamps 50 in position on the drive-shaft and automatically release the same at the end of their movement along said shaft.

2. In a machine of the kind specified a 60 screw-threaded drive-shaft, a sleeve reciprocally mounted thereon, oppositely movable clamps carried by said sleeve, having screw-threaded inner faces that engage said shaft when in operation and provided with wedge-blocks on their outer faces, a rock-spindle

the axis of which is arranged at substantially right angles to the axis of said shaft, cams mounted on the opposite ends of said spindle that engage said wedge-blocks and move the clamps toward each other, and devices that are adapted to lock said clamps 65 in position on the drive-shaft and automatically release the same at the end of their movement along said shaft.

3. A screw-threaded drive-shaft, radially movable clamps whose concave engaging 70 surfaces are screw-threaded and adapted to engage said shaft, connected rotatable cams for operating said clamps, an arm projecting from the axial portion thereof, a pivoted finger having an opposite extension and engaging and retaining said arm in a given position when said clamps engage said shaft at one end thereof, and an adjustable stationary stop that automatically releases said arm when said clamps have reached the other 75 end of said shaft.

4. In a machine of the kind specified a suitable frame therefor, a screw-threaded drive-shaft, a guide-shaft arranged parallel thereto, a sleeve reciprocal on said shafts, 80 clamps carried by said sleeve having screw-threaded inner faces that engage said drive-shaft when in operation and provided with wedge-blocks on their outer faces, a rock-spindle, cams mounted on the ends of said 85 spindle that engage said wedge-blocks and move the clamps toward each other, a latch retaining said spindle in its adjusted position, and a stationary device on the frame 90 of the machine adapted to engage and release said latch at the end of movement of 95 said sleeve in one direction.

5. In a machine of the kind specified, a suitable frame therefor, a screw-threaded drive-shaft, a guide-shaft arranged parallel 100 thereto, a sleeve reciprocal on said shafts, clamps carried by said sleeve having screw-threaded inner faces that engage said drive-shaft when in operation and provided with wedge-blocks on their outer faces, a rock 105 spindle, cams mounted on the ends of said spindle that engage said wedge-blocks and move the clamps toward each other, a stationary member on the frame of the machine, and a collar provided with lateral 110 arms one of which is provided with a latch that retains said spindle in its adjusted position and the other arm of which is adapted to engage said stationary member and release said latch at the end of movement of 115 said sleeve in one direction.

6. In a machine of the kind specified, a suitable frame therefor, a screw-threaded drive-shaft, a guide-shaft arranged parallel 120 thereto, a sleeve reciprocal on said shafts, 125 clamps carried by said sleeve having screw-threaded inner faces that engage said drive-shaft when in operation and provided with

wedge-blocks on their outer faces, a rock-spindle, cams mounted on the ends of said spindle that engage said wedge-blocks and move the clamps toward each other, a collar 5 provided with lateral arms one of which extends rearwardly and is provided with a latch that retains said spindle in its adjusted position and the other arm of which extends substantially downwardly, and a pin 10 projecting laterally from the frame of said

machine that is adapted to be engaged by said lower arm at one end of the movement of the sleeve and release said latch.

In testimony whereof I have hereunto set my hand and seal this 2nd day of November, 15 A. D., 1908.

FRANK HESS. [L. S.]
